(57) **CLAIM**

The ornamental design for a footwear midsole as shown and described.

DESCRIPTION

FIG. 1 is a front perspective view of a footwear midsole showing my new design;

FIG. 2 is a rear perspective view thereof;

FIG. 3 is a front elevational view thereof;

FIG. 4 is a rear elevational view thereof;

FIG. 5 is side elevational view thereof;

FIG. 6 is an opposite side elevational view thereof;

FIG. 7 is a top plan view thereof; and,

FIG. 8 is a bottom plan view thereof.

The dash-dash broken lines in FIGS. 1-8 represent portions of the footwear midsole and environmental structure that form no part of the claimed design. The dot-dash line which defines the bounds of the claimed design forms no part thereof.

1 Claim, 8 Drawing Sheets
